VAN BUREN MADRY

MEANS FOR CONTROLLING THE DRAFT IN AIR BLAST COTTON GINS

Filed April 15, 1925

FIG. I.

FIG. 2.

FIG. 3.

FIG. 4.

BY *Van Buren Maday*
By Loyall Miller — ATTORNEY.

UNITED STATES PATENT OFFICE.

VAN BUREN MADRY, OF FORT COBB, OKLAHOMA.

MEANS FOR CONTROLLING THE DRAFT IN AIR-BLAST COTTON GINS.

Application filed April 15, 1925. Serial No. 23,338.

To all whom it may concern:

Be it known that I, VAN BUREN MADRY, a citizen of the United States, residing at Fort Cobb, in the county of Caddo and

5 State of Oklahoma, have invented a certain new and useful Improvement in Means for Controlling the Draft in Air-Blast Cotton Gins, of which the following is a specification, reference being had to the accompanying drawings.

The object of the invention is to provide a device of the character described which will be cheap, comparatively light, strong, durable, easily installed and attached, 15 economical in its manufacture and operation; also that will control the application and draft of the air in the moting chamber in air blast cotton gins, particularly of the type of the Murray gin, control the motes and dirt preventing them from being drawn in with the products of the cotton at the mote board, and directing their being carried out through the mote and dirt conveyor; controlling the lint and other products of the cotton so as to save them, and preventing them from being carried off through the mote and dirt conveyor; also preventing the gumming up of the mote board and shield by green or damp cotton, 25 grasshoppers, spiders and such like, and preventing the lint and other products from sticking and clinging to the mote board and shield when so gummed up; and preventing back lashing and danger from fire; and 30 making a large turnout of lint, and other products; and permit the use of a much smaller mote and dirt conveyor than formerly necessary.

The invention novel features, details of 40 construction, combination of parts, and other objects of the invention will be hereinafter more particularly set forth, illustrated in the accompanying one page drawings and pointed out in the appended claims.

45 Reference is hereby made to the drawing forming a part of this application, of which,

Figure 1 is a perspective view of the adjustable mote board shield.

50 Figure 2 is a perspective view of the end of the mote board shield, in section.

Figure 3 is a perspective view of the saw draft door showing the blades practically closed.

55 Figure 4 is a sectional view of the Murray type of air blast gin showing the adjustable

mote board shield and the adjustable saw draft door mounted therein.

Like characters of reference designate 60 like parts in all figures.

The drawing shown in this instance shows the usual parts of an air blast cotton gin, particularly of the Murray type, such as air chamber 1, air duct 2, nozzle 3, duct to lint flue 4, saws 5, and moting point 6, saw 65 draft door 7 (removed when our device is used), dirt and mote conveyor 8, and 8^a moting chamber, top rib 9, bottom rib 9^a.

The adjustable saw draft door consists of a suitable metal bar 14 connected at right 70 angles with two metal ends 10, having a plurality of curved blades fastened on said ends as shown at 15, 16, 17 and 18, the upper edge of said blades being thickened 19 and the lower thinned 20. Said blades are 75 adjustable and may be opened and closed, or partially opened and set at any point desired and held in such position by fastenings 15, 16, 17 and 18. In application the saw draft door of the air blast gin, particularly of the Murray type 7 is removed and our adjustable saw draft door is placed inside their door framing the top thereof placed up against the gin top the top of adjustable saw draft door 11 leaning forwardly and inwardly, after this is battened in the bottom falls down and the notch 12 in end of plates catch on the bottom door sides. It will be observed this leaves it inside the gin leaning forward reducing the 85 distance from the moting point to the draft door, and the convexly curved blades are pointing downward and with motes striking the blades so pointed, and the air admitted 90 between said blades and directed towards the dirt and mote conveyor 8 tends to make the general circulation of air in said moting chamber from the moting point 6 to the dirt and mote conveyor 8, and in that direction only, as is shown by 21 and 22, and 95 to keep it away from the nozzle 3.

The adjustable mote board shield is a piece of hardwood susceptible of a smooth surfaced high polish, practically U-shaped, and fitting on the mote board in the valley 105 26 of said U-shaped shield, and when placed on the device is inverted. The thinner lip 23, is nearest the saw teeth 5 at the nozzle 3 and the thicker lip 24 away from them. At each end of the mote board shield is a 110 wedge shaped piece of metal 27 holding said shield in place and having near the outer

end of said wedge-shaped piece a curved slot 28 to adjustably set the shield to change the position of the shield as desired at the nozzle 3.

5 It will be seen, or at least known to those familiar with the art to which my invention relates that in the use of the ordinary air blast gin, and particularly of the type of the Murray gin, that in use with the saw draft 10 door closed the dirt and motes will be thrown from the moting point 6 against the door 7 with such force as to rebound to the nozzle 3 and be carried through lint flue 4, thereby injuring the finished product of the gin; also 15 running with the door closed there will be a considerable portion of the lint and valuable products of the gin carried away out of the moting chamber into the dirt and mote conveyor, and thereby lost. If the saw draft 20 door is left open a great deal of the dirt and motes will be carried out thereat, and with it a considerable portion of the lint and other products of the gin. It will also be seen, or known by those familiar with the art that in 25 ginning in damp weather and in ginning a great many kinds of cotton, such as green, damp, wet, and that which has in it grasshoppers, spiders, spider-balls and other insects, the saw cutting these up throws on the 30 mote board a gummy substance which freezes or sticks to the mote board, and keeps accumulating thereon with the addition of lint, streamers of cotton, and dirt, and causing streamers of cotton, lint and dirt to hang 35 over the nozzle thereby practically preventing the running and usefulness of the gin, and making it necessary at frequent intervals to stop the machinery, clean out the gummed up and clogged portions and sandpaper off the mote board. Under the present 40 system a great deal of back lashing occurs. This is brought about by portions of the lint failing to be properly discharged through the lint chamber and this eddying lint being 45 caught by the teeth and carried around through the ribs the second time. As it passes through the ribs at the bottom it is dragged off and wedged in quantities and densely packed even through the huller ribs.

50 Seed passing down the gin ribs cannot escape after being ginned and back up into the roll box. The slugs of lint and such like, are dragged from the bottom of the ribs to the top around the shoulder of the ribs and are 55 wedged in in the same manner. When this condition exists fire is frequently caused at either bottom or top point of ribs by the friction; teeth may be broken off of saws at either point; saws warped or sprung out of 60 true; ribs worn by the saws being sprung out of shape and into them; and ribs broken out by this condition. The use of the present device by removing the door and placing the adjustable saw draft door in place the distance from the moting point to the door is 65 shortened, and tends to make the general contour of the inside of the chamber and the circulation of the draft from said moting point to the dirt and mote conveyor circular; the blades prevent the dirt motes and a 70 part of the lint and products from being carried out the door into the air, and downwardly slanting position of the door and the convexly curved and downwardly slanting position of the blades prevent the dirt and 75 motes from rebounding towards the moting point 6 and nozzle 3 and being drawn into the lint flue 4 at the nozzle 3. The air from what was formerly dead air space by reason 80 of being drawn from the upper part of the saw at the moting point 6 to the dirt and mote conveyor by way of the adjustable saw draft door creates a current for carrying off the dirt and motes and heavier than lint and cotton products through the mote conveyor 85 and allows the lint and cotton products to be drawn through the aperture near the nozzle 3 into the lint flue 4. The effect of this also will be to permit of the use of a much smaller mote conveyor than at present used 90 and decrease the amount of lint now carried off through the conveyor. This will in turn also assist in permitting a much greater portion of lint (which had been formerly circulating in the dead air space in the gin and 95 carried out the mote conveyor) to be carried out at the lint flue 4 for the reason that a greater current of air can now be applied at the nozzle 3 without disturbing the dirt and motes in their travel to the conveyor from 100 the moting point 6. It will also be seen that this proper circulation of draft and the adjustable smooth highly polished hardwood mote board shield will relieve the condition 105 of the gumming up of the gin as described, and permit of the nearer closing of the aperture between the saw and the nozzle and thereby decrease the amount of dirt and motes getting into the lint flue at this place, and will prevent the forming of stringers 110 and hangers and consequent back lashing therefrom.

I claim—

1. In combination with an air blast cotton gin, an adjustable saw draft door comprising a plurality of convexed blades, a frame and means for adjustably holding same together, and means for attaching to said gin.
2. In combination with an air blast cotton gin, an adjustable saw draft door comprising a plurality of convexed blades, a frame and means for adjustably holding same together, means for suitably attaching same to said gin, an adjustable mote board shield with a wedge shaped metallic piece at each end, a curved slot in each piece near the outer edge, means for suitably attaching said shield and metal to the mote board and gin.
3. In combination with an air blast cotton

- gin, and an adjustable saw draft door, as described, an adjustable mote board shield covering the length of the mote board, shaped like an inverted **U**; a wedge shaped 5 metallic piece at each end, a curved slot in each piece near its outer edge, means for suitably attaching said shield to the mote board, and said metal to the mote board and gin.
- 10 4. In combination with an air blast cotton gin, comprising an air chamber, air duct, nozzle, duct to lint flue, saws, ribs, moting
- chamber, dirt and mote chamber, an adjustable saw draft door comprising a plurality of convexed blades, a frame and means for 15 adjustably holding same in place as desired, means for suitably attaching same to said gin, an adjustable mote board shield, a wedge shaped metallic piece at each end thereof having a curved slot in each near its 20 outer edge; means for suitably attaching said shield and metal to the mote board and gin.

VAN BUREN MADRY.
